OPERATOR'S FLUID PRESSURE CONTROL
VALVE DEVICEArthur J. Bent, Penn Township, Allegheny
County, Pa., assignor to Westinghouse Air
Brake Company, a corporation of Pennsylvania

Application April 30, 1947, Serial No. 745,074

5 Claims. (Cl. 137—623)

1

This invention relates to fluid pressure control mechanism, and more particularly to a control valve device for controlling operation of a fluid pressure actuating cylinder such as might be used for opening and closing bomb bay doors on a military airplane.

Although this invention will be described as embodied in airplane control apparatus, it will be understood that it may be embodied in other control apparatus.

During the recent war our military bombing planes would fly missions over a target area, open the bomb doors and drop their bombs on an objective. The time required for opening and closing the bomb doors was relatively long so that the enemy observing from the ground the open or opening bomb doors on the approaching aircraft were thereby forewarned of attack and immediately sent up a defensive flak barrage which reduced the effectiveness of our missions.

The principal object of the present invention is therefore the provision of an improved fluid pressure control valve device particularly adapted for use in an improved bomb door actuating mechanism which is operative to open and close bomb doors at a rate so rapid, as compared to previous mechanisms of this general type, that opening thereof need not be initiated until substantially the instant it is desired to release the bombs, following which the doors may be as quickly closed.

Other objects and advantages will become apparent from the following more detailed description of the invention.

In the accompanying drawing, the single figure is a diagrammatic, sectional view of a fluid pressure system embodying a control valve device constructed in accordance with the invention.

Description

As shown in the drawing, the reference numeral 1 designates a fluid pressure cylinder for actuating or positioning a device such as an airplane bomb door. A control valve device 2, embodying the invention, is provided for controlling operation of the cylinder 1, and an electrical operator's switch or controller 3 is provided for normally controlling said valve device 2 at a station which may be remote therefrom.

The fluid pressure cylinder 1, employed only for illustrating an application of the invention, may comprise a casing 4 in which is disposed a piston 5 which divides the interior of said casing into pressure chambers 6 and 7. End cover members 8 and 9 close outer ends of chambers 6 and 7, respectively. A piston rod 10 is provided for connecting the piston 5 to a device to be actuated (not shown) such as an airplane bomb door.

The valve device 2 comprises a casing 11 in which are disposed and spaced apart in parallel relationship one with the other two similar control valve assemblies 12 and 13 for controlling

supply of fluid under relatively high pressure from a supply pipe 14 to the respective pressure chambers 6 and 7 of cylinder 1 and its release therefrom by way of pipes 15 and 16 respectively.

5 Each assembly 12 and 13 comprises a control piston 17, and two similar pilot valve assemblies 18 and 19 are disposed in parallel and spaced apart relation in casing 11, between assemblies 12 and 13, for controlling operation of the two pistons 17. Two similar solenoids 20 and 21 are disposed adjacent the ends of the respective pilot valve assemblies 18 and 19 and arranged to actuate said assemblies. Each of the solenoids is connected to the switch 3 which controls the energization thereof. An emergency lever 22 is disposed outside casing 11 opposite the pilot valve assemblies 18 and 19 and arranged to actuate same in the event that either of the solenoids 20 and 21 should fail to operate as intended.

20 Each of the control valve assemblies 12 and 13 embodies a bore 23 open at opposite ends to two chambers 24 and 25 in the casing 11. Two similar cylindrical bushing members 26 and 27 are inserted one in each end of the bore 23 at the junction of said bore with chambers 24 and 25, respectively. The bushing member 26 in each assembly 12 and 13 is held in place by a foraminated sleeve member 28 which is disposed in chamber 24 between a removable fitting 29 and the outer end of said bushing member 26. An annular shoulder 30 is formed in the bushing member 26 which seats against a corresponding casing shoulder for locating said bushing 26 in the bore 23. Similarly, bushing member 27 is provided with an annular shoulder 31 which seats on a corresponding casing shoulder to locate said bushing member with respect to bore 23. A similar foraminated sleeve member 32 is clamped between bushing member 27 and a removable fitting 33 within chamber 25. Bushing member 26 comprises an annular seat rib 34 which projects into the end of the foraminated sleeve member 28 and encircles one end of a central chamber 35 closed at its opposite end by a wall 36. The rib 34 is provided for accommodating an exhaust valve 37 which is slidably disposed in the sleeve member 28. The bushing member 26 is provided with radial ports 38 which open the chamber 35 thereof with an annular chamber 39 formed by registering grooves 40 and 41 in bore 23 and said bushing member 26, respectively. Annular chamber 39 of valve assembly 12 is open to the corresponding annular chamber 39 in valve assembly 13 and to the atmosphere by way of a passage 42 in casing 11. Again in each valve assembly 12 and 13, the bushing member 27 is provided with a central chamber 43 which opens in from the outer end thereof adjacent chamber 25 to an end wall 44 formed therein. The chamber 43 is provided with radial through ports 45 which open said chamber 43 to an annular chamber 46 formed by reg-

35 40 45 50 55 60 65 70 75 80 85 90 95

istering grooves 47 and 48 in casing 11 and bushing member 27, respectively. A casing passage 49 connects the annular chamber 46 with the chamber 24. An annular seat rib 50 is formed in bushing member 27 encircling the open end of chamber 43 for accommodating a supply valve 51 which is slidably disposed in the sleeve member 32 and urged towards said rib 50 by a compression spring 52 which is interposed between said valve and the fitting 33. The piston 17 is slidably mounted in a cylinder formed in the bore 23 between end walls 36 and 44 of bushing members 26 and 27, respectively, and divides said cylinder into a fluid pressure chamber 54 adjacent wall 36 above said piston and a fluid pressure chamber 55 under said piston adjacent wall 44, as viewed in the drawing. A rod 56 extends from piston 17 through chamber 55, a central bore 57 in end wall 44 with which bore said rod is in sealable and slidable contact, and projects into chamber 43 of bushing member 27 for contact with supply valve 51. The projecting end of rod 56 is curved for point contact with valve 56 to allow freedom for alignment of said valve in seating on rib 50. A rod 58 extends from the opposite side of piston 17 through chamber 54 and a bore 59 in end wall 36 to project into chamber 35 of bushing member 26. The projecting end of rod 58 is provided with an annular shoulder 60, for engagement with exhaust valve 37, and with a reduced portion 61 which projects therefrom slidably through a central opening 62 in said valve 37. An exhaust valve member 63 disposed in chamber 24 is held seated on the projecting end of rod portion 61 by a compression spring 64 which is interposed between the fitting 29 and said member 63. The valve member 63 is normally disposed away from valve 37 opposite to one end of a small opening or openings 65 which extend through said valve 37 for opening chamber 24 with chamber 35 in bushing member 26.

The fitting 29 of valve assembly 12 is connected to the pipe 15 which thereby opens the chamber 24 of said assembly 12 with the fluid pressure chamber 6 of cylinder 1. The fitting 29 of valve assembly 13 is connected to the pipe 16 which thereby opens the chamber 24 of said assembly 13 with the fluid pressure chamber 7 of cylinder 1. The fitting 33 of valve assembly 12 is connected to the fluid pressure supply pipe 14 adapted to be supplied with fluid under pressure from any suitable source of fluid under pressure (not shown), while the chamber 25 of valve assembly 13 which is open to the corresponding chamber in assembly 12 by way of a casing passage 66 is also open to said source. The fitting 33 of valve assembly 13 is blanked off; its removal allows for removal and insertion of parts of said assembly as does removal of corresponding fitting 33 of assembly 12 and respective fittings 29.

The pilot valve assemblies 18 and 19 arranged in parallel and spaced apart relation, intermediate the valve assemblies 12 and 13, each comprises a bushing member 67 which is inserted in sealing engagement in a casing bore 68 and held in place by a plate member 69, removably secured to the casing by cap screws 70. Each bushing member 67 is provided with a central bore 71 which extends longitudinally therethrough and registers coaxially with a casing bore 72 for accommodating a rod shaped pilot valve 73 which extends through bores 71 and 72 in sealing engagement therewith. Two annular chambers 74 and 75 are formed and spaced apart in each bushing member 67 encircling the pilot valve 73. Each pilot valve has a bore 78 open to two spaced apart

radial ports 76 and 77, adapted in a release position of the valve, in which it is shown in the drawing, to establish communication between chamber 75 and atmosphere, and adapted in another or supply position to establish communication between chamber 74 and 75.

The annular chamber 74 in each pilot valve assembly 18 and 19 is open to the casing passage 66, extending between chambers 25 of valve assemblies 12 and 13, by way of a registering passage 66a in the respective bushing member 67. The annular chamber 75 in pilot valve assembly 18 is open to the fluid pressure chamber 54 above piston 17 in valve assembly 12 and to chamber 55 under piston 17 in valve assembly 13 by way of registering passages 79 in the respective bushing member 67 and in the casing 11. The annular chamber 75 in pilot valve assembly 13 is open to the corresponding chamber 54 in valve assembly 13 and with the corresponding chamber 55 in valve assembly 12 by way of registering passages 80 in the respective bushing member 67 of said assembly 19 and in the casing 11.

Each solenoid 20 and 21 comprises a rod 81 which is pivotally connected at its outer end to one end of a lever 82 the opposite end of which lever slidably engages with a portion of casing 11. A curved portion of each lever 82 fits around the upper projecting end of the respective pilot valve 73 to form a shoulder 83 for engagement with an annular shoulder 84 formed on a flange 85 connected to said pilot valve 73. The shoulder 84 on each pilot valve 73 is urged into engagement with shoulders 83 of the respective lever 82, which are thereby urged toward the casing, by a compression spring 86. The spring 86 acts against a piston 87 of a piston and rod member 88 which is pivotally connected at 89 to a balance member 90 equidistant from opposite ends thereof which ends are in slidable engagement with upwardly projecting ends of the pilot valves 73. The piston 87 of member 88 is slidably and guidably disposed in a bore 91 which extends into a portion of casing 11 equidistant between the solenoids 20 and 21. The spring 86 is interposed between the piston 87 and the portion of casing 11 which forms the end wall of said bore. The bore 91 is open to the atmosphere via a branch of the passage 42 in the casing 11.

The emergency lever 22 is disposed opposite to downwardly projecting end portions of pilot valves 73 and is pivotally connected at its mid-point 93 to a projecting arm 94 formed integral with casing 11. An opening 95 is formed in each of the opposite ends of said lever to provide for connection with cables or other suitable means (not shown) for actuating said lever.

The switch 3 may be of the single pole double throw type having a pole 96 connected to one pole 97 of each solenoid 20 and 21 by wires 98 and 99, and terminals 100 and 101 connected, respectively, by wires 102 and 103 to opposite poles 104 and 105 of the solenoids 20 and 21. A battery 106 is connected in wire 98 to furnish a suitable source of electrical energy for solenoids 20 and 21.

Operation

With the parts of the system in the position in which they are shown in the drawing, both terminals 100 and 101 are disconnected from pole 96 in the operator's switch 3, and both of the solenoids 20 and 21 are therefore de-energized, which permits the spring 86 to urge the pilot valves 73 of both valve assemblies 18 and 19 to their normal positions in which they are shown in the drawing. In the normal position, the port

76 in pilot valve 73 of valve assembly 18 is in registry with annular chamber 75 of said assembly and the port 77 of said valve is open to the atmosphere, thus opening the fluid pressure chamber 54 of valve assembly 12 and the fluid pressure chamber 55 of valve assembly 13 to the atmosphere by way of passages 79, said annular chamber 75, and the passage 78 in said pilot valve. The corresponding port 76 in valve 73 of valve assembly 19 is in registry with the annular chamber 75 of said assembly while the port 77 of said valve 73 is open to the atmosphere, thus the fluid pressure chamber 54 of valve assembly 13 and the chamber 55 of valve assembly 12 are opened to the atmosphere by way of passages 80, said annular chamber 75, and the corresponding passage 78 in said pilot valve.

In the absence of fluid under pressure in pressure chamber 54 in either of the valve assemblies 12 and 13 no force is thereby exerted on the pistons 17 of said assemblies in the direction of respective supply valves 51 so that the springs 52 are effective to maintain the supply valves 51 seated on the respective ribs 50, thus closing off the supply chambers 25 from the chambers 43 in the respective bushing members 27 and consequently, from the chambers 6 and 7, in cylinder 1, which are open respectively to said chambers 43 by way of pipes 15 and 16, respective chambers 24, passages 49, annular chambers 46, and ports 45. In the absence of any fluid under pressure in the chambers 55 of valve assemblies 12 and 13 acting on the respective pistons 17 the springs 64 are effective to seat the rods 56 attached to the under side of said pistons on the seated supply valves 51. Valve members 63 are disposed away from the openings 65 in the respective exhaust valves 37 which, when the valve device 2 is positioned as shown in the drawing, seat themselves on the seat ribs 34. The chambers 6 and 7 of cylinder 1 are therefore opened to the atmosphere by way of the respective chambers 24 in valve device 2, the openings 65 through valves 37, the chambers 35 and ports 38 in respective bushing members 26, annular chambers 39, and the passages 42 in casing 11 of said device 2. Assume, that the supply pipe 14 is connected to a suitable source of fluid under pressure (not shown) and that thereby the chambers 25 of both valve assemblies are charged with fluid under pressure and that both annular chambers 74 of pilot valve assemblies 18 and 19 are similarly charged by way of the passage 66.

If it is now desired to effect movement of the piston 5 in cylinder 1 from its extreme left-hand position as shown in the drawing to an opposite extreme right-hand position, the operator's switch 3 is positioned to make electrical connections between the pole 96 and terminal 100, thus effecting supply of electrical energy from battery 106 to solenoid 20 which is thereby energized, while the solenoid 21 remains de-energized.

Energization of solenoid 20 moves its rod 81 upward, raising one end of the respective lever 82 the opposite end of which remains in sliding contact with the casing 11, and in so doing by cooperation between shoulders 83 and 84 carries the pilot valve 73 of pilot valve assembly 18 upward, as viewed in the drawing, against opposition of spring 86 which is further compressed by movement of the balance member 90, one end of which slidably pivots on the upper end of corresponding valve 73 of assembly 19 as its opposite end is raised by slidable contact with valve 73 of the assembly 18.

Upward movement of pilot valve 73 of valve assembly 18 continues until the ports 76 and 77 thereof register, respectively, with annular chambers 74 and 75 in the bushing member 67 of said assembly, thereby establishing communication between said chambers by way of said ports and the passage 78 connected thereto. Fluid under pressure supplied to the respective annular chamber 74 of assembly 18, which is open to supply pipe 14 as previously described, now flows by way of the passage 78 and annular chamber 75 of said assembly 18, and casing passages 79 to the fluid pressure chamber 54 above piston 17 of valve assembly 12 and to the chamber 55 under corresponding piston 17 of valve assembly 13.

Fluid under pressure thus supplied to chamber 54 of valve assembly 12 acts on the upper face of piston 17 to cause a downward force to act through attached rod 56 on the upper face of the seated supply valve 51 of said assembly, which valve is thereby unseated by downward movement of said piston when said force becomes sufficiently great to overcome the opposing force of respective spring 52 and pressure of fluid in chamber 25 acting on the under side of said valve 51. As piston 17 of assembly 12 moves downward it carries attached rod 58 with it and allows the respective spring 64 to seat the respective valve member 63 on the exhaust valve 37 of said assembly, thereby closing the opening or openings 65 in said valve 37. Fluid under pressure is now free to flow from the supply pipe 14 to the pipe 15 and connected fluid pressure chamber 6 of cylinder 1 by way of the chamber 25, the unseated supply valve 51, the chamber 43 and ports 45 in bushing member 27, the annular chamber 46, casing passage 49, and the chamber 24, which is now closed to the atmosphere by the seated valve member 63, respectively, in valve assembly 12.

At the same time, the previously mentioned fluid under pressure supplied to chamber 55 of valve assembly 13 exerts a force on the under side of piston 17 in said assembly which acts through its attached rod 58 to unseat the respective exhaust valve 37, when said force becomes sufficiently great to overcome action of the respective spring 64. The pressure chamber 7 of cylinder 1 is now freely open to the atmosphere by way of pipe 16, chamber 24, the unseated exhaust valve 37, the chamber 35 and ports 38 in bushing member 26, annular chamber 39, all of valve assembly 13, and the passages 42 in casing 11.

A differential in pressure of fluid in chambers 6 and 7 of cylinder 1 is thereby created which is sufficiently great to move the piston 5 rapidly from its extreme left-hand position to its opposite extreme right-hand position, which movement of piston 5 carries the attached rod 10 with it, and if considered to be connected to a bomb bay door (not shown) of an airplane would thereby rapidly open it for release of bombs.

Since chamber 7 is open to the atmosphere by way of the unseated exhaust valve 37 of assembly 13 rather than by way of the relatively small opening 65 in said valve during motion of piston 5 toward chamber 7, little resistance is offered to displacement of fluid in chamber 7 to impede motion of said piston, so that it moves rapidly during its traverse.

If the cylinder 1 is employed for operating a bomb door it is desirable to release the fluid under pressure therefrom immediately after its operation to either open or close said door to

prevent explosion of said cylinder if ruptured by flak or the like.

To thus release fluid under pressure from cylinder 1 after it has been moved to its right-hand position, the operator's switch 3 is moved to break contact between the pole 96 and terminal 101, and thereby de-energize the solenoid 20. The spring 86 acting through piston member 88 and balance member 90 becomes effective to return the pilot valve 73 of pilot valve assembly 18 to its normal position, as shown in the drawing, carrying with it the respective rod 81 and lever 82.

The annular chamber 74 of the pilot valve assembly 18 is thereby again disconnected from the adjacent annular chamber 75 which is again open to the atmosphere by way of opening 76, passage 78, and opening 77 in pilot valve 73 of said assembly 18. Fluid under pressure previously supplied to chambers 54 and 55 of valve assemblies 12 and 13, respectively, is now vented to the atmosphere by way of passages 79 connected to the annular chamber 75 of pilot valve assembly 18.

Pressure of fluid is again equalized in chambers 54 and chambers 55 on opposite sides of pistons 17 in both valve assemblies 12 and 13. In assembly 12, the spring 52 becomes effective to close the supply valve 51, return the piston 17 and attached rods 56 and 58 to their normal position as shown in the drawing, and thereby unseat the exhaust valve member 63 from the exhaust valve 37. In assembly 13, the spring 64 acting through valve member 63 and rod 58 becomes effective to move the piston 17 and attached rod 56 downwardly to its normal position limited by engagement of said rod 56 with the upper surface of the seated supply valve 51, thereby allowing the exhaust valve 37 to reseat on the rib 34 of bushing member 26.

Fluid under pressure in chamber 6 of cylinder 1 is now vented to atmosphere by way of pipe 15 and, in valve assembly 12, the chamber 24, the unseated valve member 63, opening or openings 65 in exhaust valve 37, the chamber 35 and ports 38 in bushing member 26, and annular chamber 39 and passage 42 in casing 11.

Now assume that it is desired to return the piston 5 of cylinder 1 to its extreme left-hand position, as shown in the drawing. The operator's switch 3 is positioned to make contact between pole 96 and terminal 101 to thereby effect energization of solenoid 21 while solenoid 20 remains de-energized.

Upon energization of solenoid 21, the rod 81 of said solenoid, acting through the lever 82 attached thereto, raises the pilot valve 73 of pilot valve assembly 19 upward against opposition of spring 86 acting thereon through member 88 and balance member 90 in manner similar to action as previously described with respect to energization of solenoid 20. The pilot valve 73 of the pilot valve assembly 19 is thus so positioned as to connect, by way of passage 78, annular chambers 74 and 75 of said assembly. Fluid under pressure supplied to annular chamber 74 of assembly 19, which is open to supply pipe 14, as previously described, is therefore now free to flow to fluid pressure chamber 54 above piston 17 in valve assembly 13 and to chamber 55 under corresponding piston 17 in valve assembly 12. The differentials in pressures of fluid across the pistons 17 in assemblies 12 and 13 causes piston 17 in the former assembly to move upward and piston 17 in the latter assembly to move down-

ward, which is just the reverse of the previous action described with respect to energization of solenoid 20. It will readily be seen, therefore, that in valve assembly 12 this movement of piston 17 and attached rod 58 unseats the exhaust valve 37 and thereby freely opens the pressure chamber 6 to the atmosphere by way of the pipe 15, said assembly 12, and the casing passages 42. Also it will be seen that in valve assembly 13 downward movement of piston 17 and attached rods 58 and 56 allows the spring 64 to become effective to seat valve member 63 on valve 37, closing opening 65 therethrough, and overcomes pressure of fluid in chamber 25 and of spring 52 acting on supply valve 51 to thereby unseat said valve 51. Fluid under pressure now flows from the supply pipe 14, through chamber 25 in valve assembly 12, casing passage 66, and in the valve assembly 13 the corresponding chamber 25, past the unseated supply valve 51 thence through chamber 43 and ports 45 in bushing member 27, passage 49 and chamber 24, which is now closed to atmosphere by the seated exhaust valve member 63, to the pipe 16 and fluid pressure chamber 7 in cylinder 1. Differential in pressures of fluid in chambers 6 and 7 across piston 5 now causes said piston to move rapidly from its extreme right-hand position to its extreme left-hand position, in which it is shown in the drawing.

Now to release or vent fluid under pressure from the fluid pressure chamber 7 of cylinder 1, in a manner similar to that previously described, the operator's switch 3 is positioned to break the contact between the pole 96 and terminal 101 to thereby de-energize solenoid 21, while solenoid 20 remains de-energized. The spring 86 now becomes effective to return the pilot valve 73 of pilot valve assembly 19 to its normal position in which it is shown in the drawing, thereby disconnecting annular chamber 74 from annular chamber 75 of said assembly and connecting the last named chamber to the atmosphere by way of passage 78 in said pilot valve. Fluid under pressure is now vented from chamber 54 of valve assembly 13 and from chamber 55 of valve assembly 12 by way of passages 80 and the now normally positioned pilot valve assembly 19. In assembly 13, the spring 52 now becomes effective to reseat the supply valve 51 and unseat the exhaust valve member 63 by returning piston 17 and attached rods 56 and 58 to normal position. Fluid under pressure from the chamber 7 of the cylinder 1 is now vented to the atmosphere by way of the pipe 16 and, in the valve assembly 13, the chamber 24, the unseated valve member 63, opening 65 in valve 37, chamber 35 and ports 38 in bushing member 26, annular chamber 39 and passages 42 in casing 11. At the same time, in valve assembly 12, the spring 64 is rendered effective by release of fluid under pressure in chamber 55 to return piston 17 and attached rods 58 and 56 to normal position, allowing exhaust valve 37 to reseat on rib 34.

After fluid under pressure is supplied to chamber 6 or 7 of cylinder 1 for moving piston 5 to either one of its opposite positions and the switch device 3 is positioned as shown in the drawing, the fluid under pressure is vented from said chamber past either of the unseated valve members 63 which is opened by a respective spring 52, as previously described. These valve members 63 seat over the opening or openings 65 in exhaust valves 37, the sum area of which openings 65 is relatively small compared to the area of the

openings in bushing members 26 closed by valves 37. The valve members 63 are employed in the manner set forth in preference to opening the valves 37 against opposition of action of pressure of fluid in chamber 24 so as to require springs 52 of lower spring constant and smaller size, and pistons 17 of smaller area, than would otherwise be required, and due to which, the control valve device 2 can be smaller in size and lighter in weight.

In the event that either solenoid 20 or 21 should fail to operate, the pilot valves 73 of pilot valve assemblies 18 and 19 in the valve device 2 may be operated by the emergency lever 22 which responds to a pull as thrust on either end, as the case may be, to move one of said valves 73 upwardly in fashion similar to movement by either of the solenoids 20 or 21 for the same purpose and with the same results.

Summary

From the above description, it will now be seen that I have provided a control mechanism for operating a bomb door of an airplane quickly and positively in response to suitable operation of the operator's control device, embodying the invention. The operator's control device is relatively simple, compact and light in weight, as required for such use, and is operative by a relatively small pilot force for controlling actuating fluid to the operating cylinder at such pressure and in such an amount as necessary to obtain the desired speed of operation of the piston in said cylinder. The actuating fluid is preferably in the form of compressed air, and the operator's control device provides for dissipating the compressed air from the operating cylinder immediately at the end of obtaining a desired operation so as to minimize possibility of explosion of the cylinder if hit by a flying missile.

While one illustrative embodiment of the invention has been described in detail, it is not my intention to limit its scope to that embodiment or otherwise than by the terms of the appended claims.

Having now described my invention, what I claim as new and desire to secure by Letters Patent, is:

1. In a fluid pressure valve device the combination with a casing having a through bore open at one end to a fluid pressure supply chamber and at the opposite end to a control chamber, a first valve seat bushing member sealably mounted in said bore having an exhaust valve seat formed therein around one end of a central chamber opening into said control chamber and also having an end wall formed therein closing the opposite end of said central chamber, said central chamber being open also to atmosphere by way of radial ports through said bushing member and a casing passage registering therewith, an exhaust valve slidably disposed in said control chamber, spring means for urging said exhaust valve to seat on said exhaust valve seat, a second valve seat bushing member sealably mounted in said bore opposite to said first bushing member and spaced away therefrom and having an annular supply valve seat formed therein at one end of a central chamber open to said supply chamber and also having an end wall formed therein closing the opposite end of the central chamber, the last named chamber being open also to said control chamber by way of ports through said second bushing and a registering casing passage, a supply valve slidably disposed

in said supply chamber, spring means for urging said supply valve to seat on said supply valve seat, a fluid pressure piston means slidably disposed in said bore between the bushings and having a fluid pressure chamber at each of the opposite sides thereof and comprising valve actuating rods attached thereto and projecting centrally therefrom through the end walls of the valve bushings for engagement with said exhaust valve and said supply valve, respectively, pilot valve means for controlling supply of fluid under pressure to either one of said fluid pressure chambers for operating said piston to unseat either the respective supply valve or exhaust valve, and means for actuating said pilot valve means.

2. A valve device comprising, a casing having a first and a second control opening, a fluid pressure supply opening and a fluid pressure exhaust opening, first normally closed supply valve means

20 for opening and closing communication between said supply opening and said first control opening, second normally closed supply valve means for opening and closing communication between said supply opening and said second control

25 opening, first normally closed exhaust valve means for opening and closing communication between said first control opening and said exhaust opening, second normally closed exhaust valve means for controlling communication be-

30 tween said second control opening and said exhaust opening, first fluid pressure piston means for actuating said first valve means, second fluid pressure piston means for actuating the second valve means, and means comprising two spaced

35 apart rod like pilot valves one being operative to supply fluid under pressure to said first piston means for opening said first supply valve means and to said second piston means for opening said second exhaust valve means and the other being

40 operative to supply fluid under pressure to said first piston means for opening said first exhaust valve means and to said second piston means for opening said second supply valve means, a beam

45 engaging adjacent ends of said valves, resilient means acting on said beam urging said valves in one direction, two levers, one for each of said valves, through which said valves may be urged in the opposite direction, a solenoid for each lever operable upon energization to actuate the respective lever, and manually operative lever means

50 fulcrumed on the casing and engaging the opposite ends of said valves for selectively actuating same.

3. A fluid pressure valve device comprising a casing enclosing a supply chamber, a delivery chamber and an exhaust chamber, a supply valve seat, an exhaust valve seat, a fluid pressure supply valve cooperable with said supply valve seat to control fluid pressure communication between said delivery chamber and said supply chamber, an oppositely seating fluid pressure exhaust valve cooperable with said exhaust valve seat to control fluid pressure communication between said delivery chamber and said exhaust chamber, a piston

60 having a pressure chamber at each of its opposite sides and interposed between said supply valve and said exhaust valve, a first rod extending from one side of said piston for unseating

65 said supply valve upon movement of said piston by fluid under pressure in the pressure chamber at the opposite side of said piston, a second rod extending from said opposite side of said piston for unseating said exhaust valve upon movement of said piston by fluid under pressure

70 in the pressure chamber at said one side of said

piston, means providing for movement of said second rod relative to said exhaust valve, when seated, upon movement of said piston to open said supply valve, a compression spring cooperable with said casing and with said supply valve to urge the latter toward said supply valve seat, a small opening from said delivery chamber encircled by an exhaust valve member seat, an exhaust valve member cooperable with said exhaust valve member seat to control communication through said small opening between said delivery chamber and said exhaust chamber and adapted to be unseated by said second rod upon seating of said supply valve by said compression spring, a bias spring cooperable with said casing to seat said exhaust valve member upon movement of said piston to open said supply valve, said exhaust valve member being relatively small with respect to said exhaust valve, and means for selectively supplying fluid under pressure to and releasing fluid under pressure from the pressure chambers.

4. A fluid pressure valve device comprising a casing enclosing a supply chamber, a delivery chamber and an exhaust chamber, a supply valve seat, an exhaust valve seat, a fluid pressure supply valve cooperable with said supply valve seat to control fluid pressure communication between said delivery chamber and said supply chamber, an oppositely seating fluid pressure exhaust valve cooperable with said exhaust valve seat to control fluid pressure communication between said delivery chamber and said exhaust chamber, a piston having a pressure chamber at each of its opposite sides and interposed between said supply valve and said exhaust valve, a first rod extending from one side of said piston for unseating said supply valve upon movement of said piston by fluid under pressure in the pressure chamber at the opposite side of said piston, a second rod extending from said opposite side of said piston for unseating said exhaust valve upon movement of said piston by fluid under pressure in the pressure chamber at said one side of said piston, means providing for movement of said second rod relative to said exhaust valve, when seated, upon movement of said piston to open said supply valve, a compression spring cooperable with said casing and with said supply valve to urge the latter toward said supply valve seat, a small opening extending through said exhaust valve between said delivery chamber and said exhaust chamber, an exhaust valve member seat formed in said exhaust valve and encircling said small opening, an exhaust valve member cooperable with said exhaust valve member seat for controlling communication through said small opening, said second rod having a portion of reduced cross section extending centrally through said exhaust valve for unseating contact with said exhaust valve member upon seating of said supply valve by said compression spring, a bias spring acting on said exhaust valve member for seating same upon movement of said piston to unseat said supply valve, and means for selectively supplying fluid under pressure to and releasing fluid under pressure from the pressure chambers.

5. A fluid pressure valve device comprising a casing enclosing a supply chamber, a delivery chamber and an exhaust chamber, a supply valve seat, an exhaust valve seat, a fluid pressure supply valve cooperable with said supply valve seat to control fluid pressure communication between

said delivery chamber and said supply chamber, an oppositely seating fluid pressure exhaust valve cooperable with said exhaust valve seat to control fluid pressure communication between said delivery chamber and said exhaust chamber, a piston having a pressure chamber at each of its opposite sides and interposed between said supply valve and said exhaust valve, a first rod extending from one side of said piston for unseating said supply valve upon movement of said piston by fluid under pressure in the pressure chamber at the opposite side of said piston, a second rod extending from said opposite side of said piston for unseating said exhaust valve upon movement of said piston by fluid under pressure in the pressure chamber at said one side of said piston, means providing for movement of said second rod relative to said exhaust valve, when seated, upon movement of said piston to open said supply valve, a compression spring cooperable with said casing and with said supply valve to urge the latter toward said supply valve seat, a small opening extending through said exhaust valve between said delivery chamber and said exhaust chamber, an exhaust valve member seat formed in said exhaust valve and encircling said small opening, an exhaust valve member cooperable with said exhaust valve member seat for controlling communication through said small opening, said second rod having a portion of reduced cross section extending centrally through said exhaust valve for unseating contact with said exhaust valve member upon seating of said supply valve by said compression spring, a bias spring acting on said exhaust valve member for seating same upon movement of said piston to unseat said supply valve, two passages in said casing connected to the two pressure chambers, respectively, two spaced apart and parallel arranged rod like pilot valves having a normal position for opening said passages to atmospheric and being operable selectively upon movement out of their respective normal positions to supply fluid under pressure to one or the other of said passages, a rockable beam extending between and engaging adjacent ends of said pilot valves, a spring acting on said beam for urging said pilot valves to their normal positions, and means for individually moving said pilot valves out of their normal positions.

ARTHUR J. BENT.
